US0D1108987S

(12) **United States Design Patent** (10) **Patent No.:** **US D1,108,987 S**
(45) **Date of Patent:** **** Jan. 13, 2026**

(54) **MEASURING INSTRUMENT**

(71) Applicant: **TLV CO., LTD.**, Kakogawa (JP)

(72) Inventors: **Takahiro Mori**, Kakogawa (JP);
Shingo Ito, Kakogawa (JP); **Yoshihiro Ito**, Kakogawa (JP); **Takahiro Hisai**, Osaka (JP); **Kenkichi Kamada**, Osaka (JP)

(73) Assignee: **TLV CO., LTD.**, Hyogo (JP)

(**) Term: **15 Years**

(21) Appl. No.: **35/522,094**

(22) Filed: **Jul. 17, 2024**

(80) **Hague Agreement Data**

Int. Filing Date: **Jul. 17, 2024**

Int. Reg. No.: **DM/239444**

Int. Reg. Date: **Jul. 17, 2024**

Int. Reg. Pub. Date: **Aug. 30, 2024**

(30) **Foreign Application Priority Data**

Jan. 25, 2024 (JP) ..... 2024-001404 D

(57) **CLAIM**

The ornamental design for measuring instrument as shown and described.

DESCRIPTION

1. Measuring instrument

1.1 : Front

1.2 : Back

1.3 : Left

1.4 : Right

1.5 : Top

1.6 : Bottom

1.7 : Perspective

1.8 : Perspective

1.9 : reference perspective view

The discontinuous thin lines are ridgelines that represent three-dimensional shapes; 1.1 front view; 1.2 back view; 1.3 left side view; 1.4 right side view; 1.5 top view; 1.6 bottom view; 1.7 perspective view; 1.8 perspective view; 1.9 reference perspective view showing a state in which the measuring instrument is equipped with a cap; the broken lines in reproduction 1.9 form no part of the claimed design.

1 Claim, 9 Drawing Sheets
